(57) **CLAIM**

I claim, the ornamental design for the wall mounted hook, as shown and described.

DESCRIPTION

FIG. 1 is a perspective front view of a wall mounted hook;
FIG. 2 is a perspective rear view of the wall mounted hook;
FIG. 3 is a front view of the wall mounted hook;
FIG. 4 is a rear view of the wall mounted hook;
FIG. 5 is a first side view of the wall mounted hook, the opposite side view being a mirror image thereof;
FIG. 6 is a top view of the wall mounted hook; and,
FIG. 7 is a bottom view of the wall mounted hook.
